UNITED STATES PATENT OFFICE

2,476,834

OIL-BURNING TOBACCO CURER

Floyd M. Chilton, Sanford, N. C.

Application November 21, 1947, Serial No. 787,346

5 Claims. (Cl. 126—94)

1

This invention comprises novel and useful improvements in an oil burning tobacco curer and more specifically pertains to an improved construction of oil burner for use in such a heating system.

The principal object of this invention resides in providing an improved means for furnishing heated air for curing tobacco; and more specifically resides in a novel and advantageous construction of improved oil burner for use therein.

A prime feature of the invention resides in the provision of an oil burner unit, having an improved vaporizing unit mounted therein; in conjunction with an improved baffle means overlying the vaporizer; combined with novel air passage means through the baffle means for effectively mixing with the fuel jets from the vaporizer; and further accompanied by novel oil drainage means, vaporizer mounting means and further details of construction.

A final important feature of the invention to be specifically enumerated herein, resides in the provision of a burner unit which shall comprise a combined burner and vaporizer, which shall be of lightweight construction, simple and economical to manufacture, easy to install, and yet dependable and economical in its use.

These, together with various ancillary objects of the invention which will later become apparent as the following description proceeds, are attained by this device, a preferred embodiment of which has been illustrated, by way of example only in the accompanying drawings, wherein:

Figure 1 is an elevational view, through an air stove whose front end has been removed to permit inspection of the interior thereof, such as is particularly adapted for use in supplying heated air for curing tobacco and the like;

Figure 2 is an enlarged vertical sectional view through one of the burner units of the heating device, and taken substantially upon the vertical plane of the section line 2—2 of Figure 1;

Figure 3 is a further enlarged detail view through a portion of the vaporizer unit of the device, taken substantially upon the vertical transverse plane of the section line 3—3 of Figure 2;

Figure 4 is a side elevational view of the burner unit, taken from the left of Figure 2;

Figure 5 is a front elevational view, upon an enlarged scale, of the novel vaporizing unit of the invention;

Figure 6 is a top perspective view of the vaporizer shown in Figure 5; and,

Figure 7 is a horizontal sectional detail view taken substantially upon the plane of the broken section line 7—7 of Figure 2 and illustrating the arrangement of the air baffle and vaporizer and burner means in accordance with this invention.

Referring now more specifically to the accompanying drawings, wherein like numerals design-

2

nate similar parts throughout the various views, attention is directed first to Figure 1, wherein the numeral 10 indicates a portion of the enclosing casing or housing of an air heating device, and associated with which is a fuel supply tank or reservoir 12, suitably connected as by a conduit 14 with each of a pair of burner units indicated generally at 16. Although but two burner units have been shown in the embodiment of Figure 1, it will be understood that the principles of the invention are applicable to any number of burner units which it is desired to operate.

The burner units are mounted in what may be called a parallel arrangement, each unit having individual air inlet conduits 18 extending from the exterior of the casing 10, and being provided with a combustion product discharge conduit 20, extending from the discharge end of the burner unit, and then being joined as at 22 to merge into a common combustion product discharge pipe 24 or stack extending exteriorly of the casing 10 and through the roof of a barn (not shown) to create a draft through the burner units.

As shown best in Figure 2, each of the burner units 16 are attached as by support means 26 to a supporting surface 28 which may be a part of or carried by a portion of the casing 10, as desired.

The burner unit preferably comprises a cylindrical conduit section or open-ended casing 30 whose inlet and discharge ends are externally tapered as at 32 and 34 respectively to provide a sliding fit with the interior surfaces of the inlet and discharge conduits 18 and 20 between which the burner unit is mounted.

Intermediate its ends, the casing 30 is provided with an annular flange 36 for the purpose of mounting an annular disk-like baffle 38 as by fastening screws 40.

Likewise disposed in the wall of the casing 30 and on the air inlet side of the flange 36, is an inspection opening having a closure or manhole 44, for obtaining access to the casing for inspecting or servicing the parts therein.

Slightly spaced from the baffle 38 and positioned within the discharge portion of the casing 30, is a raised pad constituting a support, indicated at 46. This pad is provided with a flange or projection 48, rigidly or integrally attached thereto, for receiving a fastening bolt or stud 50 for a purpose to be later set forth.

Opposite the supporting pad 46, the casing 30 is provided with an aperture 52 through which extends the inlet end of a vaporizing unit consisting of a block 54 which as shown best in Figures 3, 5 and 6, constitutes a base, and which is provided with a longitudinally extending portion 56 which may be of any suitable cross-section, such as round, square, rectangular or the like. As seen clearly in Figures 3 and 7, the block 54 is spaced from the wall of the casing 30 to

provide a communication with the interior of the discharge portion of the casing 30. Extending longitudinally through the portion 56, is a bore 58 which is open at each end of the body 54, the inner end being closed by a removable plug 60, while its outer end receives a fuel supply conduit 62, connected with the above mentioned conduit 14.

As indicated best in Figure 2, the base 54 is disposed at its bottom surface transversely to the cylindrical casing 30, while the axis of the bore 58 is disposed in its inclined position relative to the bottom surface, and extends upwardly from its fuel inlet end at 62 to its closed end 60. In the embodiment shown in Figure 1, the elevation of the fuel supply 12 is preferably greater than that of the vaporizer unit 54, a suitable float means (not shown) in the fuel container being provided to assure the maintenance of a desired head upon the fuel supplied to the vaporizer. The vaporizer unit thus rests or seats upon the supporting head 46, and has its inlet end extending through the aperture 52, and is retained in this position as by the bolt 50 passing through the supporting flange 48 and engaging into the flanged face 54 of the vaporizer.

As shown more clearly in Figures 3, 5 and 7, the upper surface of the portion 56 is provided with a plurality of rows of radially disposed fuel discharge ports 64, two such rows being shown in the embodiment depicted. These discharge ports preferably open in the direction of the air inlet, 18, whereby the vaporized fuel emitted by the bores 64 will take the direction indicated by the arrows in Figure 3, being ejected against the flow of the air inlet from the inlet end 18, in order to insure a better mixing of the flowing air stream and the vaporized fuel. Any suitable ignition means may be provided for initiating combustion of the mixture of vaporized fuel and air, such means being of conventional design and not illustrated in this embodiment. Obviously, if desired, the ignition may be initiated by removing the opening 44, and inserting therethrough any suitable flame or igniter.

The device as so far described, operates as follows. Liquid fuel is supplied by means of the conduit 62 into the internal bore 58 of the vaporizer unit, and ignited by any suitable combustion initiating means. The burning fuel is then carried by the incoming air across the vaporizer unit 54, thereby highly heating the same and assisting in further vaporizing fuel delivered to the bore thereof. The combustion products are discharged from the end 20 of the device, for the purpose previously mentioned.

In accordance with the principles of this invention, the baffle means provided very greatly enhances the efficiency of the device. This baffle 38 preferably comprising a disk of circular shape conforming generally in size and shape to the internal dimensions of the casing 30, is provided with a generally rectangular air passage 66 extending therethrough as shown in Figure 7 and coincides in width with the diameter of the tubular portion 56 of the vaporizer 54. This air passage is positioned in alignment with but overlying the longitudinal axis of the portion 56, and is spaced slightly on the air inlet side of the vaporizer. This aperture serves the purpose of directing the incoming air stream from the inlet 18, directly upon the vaporized fuel discharge port 64 for producing a turbulence increasing the efficiency of the mixture of the gas and air.

Further, the flames of the burning mixture of vaporized fuel from the ports 64 and the incoming air from the inlet 18, are directed against the lower surface of the baffle 38, and thence turned backwardly towards the discharge end 20 of the device. This baffling effect thus serves to further intensify the flames played upon the vaporizer 54, thereby augmenting the efficiency of the same.

From the foregoing, the principles of operation of the invention will be readily understood and further explanation is believed to be unnecessary. Since numerous modifications will readily occur to those skilled in the art after a consideration of the foregoing specification and annexed drawings, it is not intended to limit the invention to the exact construction shown and described, but all suitable modifications and equivalents may be resorted to falling within the scope of the appended claims.

Having described the invention what is claimed as new is:

1. An oil burner construction including a vertical burner casing having a combustion chamber therein, an air inlet at one end and a combustion product outlet at the other end of said casing, a vaporizer disposed transversely of said casing between said inlet and outlet, said vaporizer comprising a body having a longitudinal bore therein, said bore being closed at one end and having a fuel inlet at the other end, said bore being upwardly inclined from said fuel inlet to its closed end, said bore being provided with a plurality of fuel discharge ports opening radially outwardly of said bore in the direction of said air inlet, a baffle secured in said combustion chamber on the air inlet side of said vaporizer, and said baffle being provided with an air passage extending therethrough.

2. The combination of claim 1 wherein said casing has a support pad on one wall thereof, a mounting flange on said pad, said vaporizer body being seated on said pad and secured to said flange.

3. The combination of claim 2 wherein the fuel inlet end of said body extends exteriorly of the wall of said casing.

4. The combination of claim 1 wherein said baffle comprises an annular plate and the air passage provided in said baffle is a substantially rectangular aperture overlying said body and said fuel discharge ports.

5. The combination of claim 4 including an annular internal flange being in said casing, said baffle secured to said annular flange.

FLOYD M. CHILTON.
